UNITED STATES PATENT OFFICE.

HENRY KAUFFMAN, DECEASED, LATE OF SEATTLE, WASHINGTON; BY MINETTE R. KAUFFMAN, ADMINISTRATRIX, OF SEATTLE, WASHINGTON.

JOIST-SUPPORTING STIRRUP.

Application filed March 12, 1925. Serial No. 14,882.

To all whom it may concern:

Be it known that I, MINETTE R. KAUFFMAN, a citizen of the United States, residing at Seattle, in the county of King and State 5 of Washington, am the administratrix of the estate of HENRY KAUFFMAN, deceased, late a citizen of the United States, late residing at said Seattle, and who was the inventor of certain new and useful Improvements in 10 Joist-Supporting Stirrups; and I do hereby declare the following to be a full, clear, and exact description of the said invention.

This invention relates to stirrups such as used for connecting joists and beams of floor 15 frames in building structures.

The object of my invention is to provide an inexpensively constructed stirrup of this character which will be of light weight, strong and rigid and afford an efficient connection between the timbers of floor framing.

Other objects and advantages of the invention will appear in the following specification.

25 The invention consists in the novel construction, adaptation and combination of parts, hereinafter described and claimed.

In the accompanying drawing,—

Figure 1 is a front elevation of a joist 30 stirrup embodying the invention. Fig. 2 is a rear elevation of the same. Fig. 3 is a plan view of a portion of a floor frame with the improved stirrups applied thereto. Figs. 4 and 5 are vertical sectional views 35 through 4-4 and 5-5 of Fig. 3. Fig. 6 is a side elevation of a modified form of the invention.

In carrying out the invention there are 40 provided two substantially U-shaped hangers, indicated generally by A and B in Figs. 1 and 2, constructed of angle bars which are each formed to provide a horizontal central portion 10 depending from parallel side portions 11 and 12.

45 The web elements 10¹, 11¹ and 12¹ of said hangers are disposed in a vertical plane and the flange elements 10², 11², and 12² protrude forwardly therefrom. Two of said hangers are disposed side by side to have the flange 50 elements 11² juxtaposed with each other and the hangers are rigidly secured, as by rivets 13, to the back of a horizontally disposed coupling bar, such as a channel bar 14 or, as shown in Fig. 6, to spaced horizontal 55 angle bars 14¹ and 14².

A coupling bar is of greater length than the combined widths of the associated hangers and in each of the protruding bar ends 15 is provided an aperture 16. To apply the above described stirrup, a floor beam as 60 17 (Figs. 3, 4 and 5) is recessed to receive therein a coupling bar 14 so that the back surface 18, Figs. 4 and 5, of the hanger members of a stirrup will bear against the adjacent side 19 of the beam. 65

The beam recess for the bar 14 is, moreover, formed to provide seating surfaces 20 and 21 for the bar flanges 22 and 23 whereby the weight of the stirrup and the load carried thereby is directly supported by the 70 beam to which it is secured by bolts 24 extending therethrough and the respective apertures 16.

By arranging two hanger members in side by side relations the two flanges 11² furnish 75 a central rib of twice the tensile strength of the flange 12² at each side of the stirrup which is advantageous where the joists, as 25 or 26, have to carry heavy loads.

Where twin joists as 25, see Fig. 3, are 80 used such central rib, comprising flanges 11², also serves to space the companion joists.

Where a single joist, as 26 at the right hand side of Fig. 3, is to be supported by a stirrup, a vertical groove 27 is provided in 85 the end of the joist to accommodate the flange 11².

The stirrups are desirably constructed of steel bars of standard shapes.

From the foregoing description the advantage of the construction and manner of applying the invention will be readily apparent; and while the preferred embodiment of the invention is illustrated and described, changes may be made therefrom within the 95 scope of the following claims.

What is claimed is,—

1. In a joist supporting stirrup, the combination of two substantially U-shaped hangers formed of angle-bars, a horizontally disposed channel bar secured to said hangers to rigidly couple the same in side-by-side relations, said channel bar being arranged to have the flange elements thereof extend rearwardly of the hangers and adapted to 100 seat within recesses provided within a supporting beam. 105

2. A joist supporting stirrup comprising a pair of U-shaped hanger members formed of angle bars arranged in side-by-side re- 110

- lations to afford a vertical flange at each side of the pair of hangers and two vertical flanges at the midwidth of the pair of hangers, and a horizontally disposed coupling-bar arranged transversely of the stirrup and rigidly secured to both of the hangers, said coupling-bar being of greater length than the combined width of the hanger members and adapted to seat upon a beam within a recess provided for the coupling-bar therein.
3. A joist supporting stirrup comprising a horizontal channel-bar provided with rearwardly extending flange elements adapted to engage upon seating surfaces provided therefor in a beam and two hanger members formed of angle-bars rigid with said channel-bar, said angle-bars having their flange elements extending forwardly.

4. A joist supporting stirrup comprising a pair of hanger members formed to substantially U-shapes and with forwardly extending flanges which are arranged to provide a horizontal seat for a joist end and a vertical rib at about the midwidth of the stirrup, and a horizontally disposed channel bar of greater length than the combined widths of said hangers, said channel bar being rigidly secured to the backs of said hangers and having its flanges extend rearwardly to provide two bearings adapted to seat upon supports provided therefor in a floor beam.

MINETTE R. KAUFFMAN,
Administratrix of the Estate of Henry Kauffman, Deceased.
